UNITED STATES PATENT OFFICE

162,794

HANDSAW

Bernard A. Derr, Columbus, Ohio, assignor to Larsan Manufacturing Company, Columbus,
Ohio, a corporation of Ohio

Application October 8, 1949, Serial No. 5,384

Term of patent 14 years

(Cl. D93—4)

To all whom it may concern:

Be it known that I, Bernard A. Derr, a citizen of the United States, residing at Columbus, in the county of Franklin and State of Ohio, have invented a new, original, and ornamental Design for a Hand Saw, of which the following is a specification, reference being had to the accompanying drawing, forming a part thereof.

Fig. 1 is a front elevational view of a hand saw showing my new design;

Fig. 2 is a top plan view thereof;

Fig. 3 is a transverse sectional view taken on the line 3—3 of Fig. 1.

I claim:

The ornamental design for a hand saw, substantially as shown.

BERNARD A. DERR.
